MATCH PACKAGE

Filed Sept. 10, 1925

FIG. 1.

FIG. 2.

FIG. 3.

Hosea T. Bradner INVENTOR

By *Rickey, Slough & Watta* ATTORNEYS

UNITED STATES PATENT OFFICE.

HOSEA T. BRADNER, OF CLEVELAND, OHIO.

MATCH PACKAGE.

Application filed September 10, 1925. Serial No. 55,477.

My invention relates to match packages or wardly to provide easy access to the matches the like and relates more particularly to that type of match package commonly known as the vest pocket type which is usually constructed of paper or cardboard or other suitable material.

One of the objects of my invention is to construct a match package of the vest pocket type wherein a protected match igniting surface is formed as part of the match package.

Another object of my invention is to construct such a match package of the character referred to whereby a cartridge of matches may be enclosed therein and whereby suitable match scratching surfaces are provided to form a match-head receiving recess.

Another object of my invention is to construct a match package having match scratching surfaces thereon and so arranged to prevent the emission of spark therefrom, thereby protecting the user and adjacent objects against contact with hot sparks.

A further object of my invention is to provide a match package of simple and economical construction whereby production may be greatly increased.

Other objects and advantages of my invention will become apparent as the description of an embodiment of my invention progresses, reference being had to the accompanying drawing forming a part of this specification and in which like characters are employed to designate like parts throughout the same.

Fig. 1 is a perspective view of one embodiment of my improved match package;

Fig. 2 is an end elevation of the same;

Fig. 3 is a bottom view of the same showing the match igniting surfaces and how the package is held while in use; and

Fig. 4 is a perspective view of another embodiment of my invention.

In the drawings, Figs. 1, 2 and 3 which are illustrative of one embodiment of my invention I provide a match package consisting of a back 1, a cover 2, an intermediate spacing portion 4' forming the top of the package, and a match cartridge retaining flap 3. A cartridge of matches 4 is secured between the back 1 and the flap 3 by means of a staple or other fastener 5.

My improved match package is preferably formed of a single sheet or strip of material such as paper or cardboard of substantial thickness to provide a rigid package, yet which will have a degree of flexibility permitting the cover 2 and back 1 to be bent back-

wardly to provide easy access to the matches held within the package.

As stated above the package is preferably formed from a sheet or strip of material. In forming the packages as shown in Figs. 1, 2 and 3, illustrating one embodiment of my invention, a portion of the material intermediate the back 1 and the flap 3 is bent upwardly transversely as at 6, then is bent over and then downwardly as at 7 and is then continued upwardly to form the flap 3. In this manner I have provided a transverse channel or groove of sufficient depth and width to conveniently receive the headed end 9 of a match 8. The inner surfaces of this channel are preferably coated with an abrasive material 10, for providing match head scratching surfaces, the coating preferably covering the entire inner area of the channel, although I may provide such coating in the extreme inner portion of the channel, or I may provide the coating only along the facing inner side walls of the channel. I may also employ other means of providing roughened surfaces with which the match head comes into contact when drawn through the channel for ignition. Such means may include roughening the inner surfaces of the channel by disturbing the surfaces of the material of the package within the channel, or by affixing within the channel, a metallic or other plate having its exposed surfaces roughened for engagement with the match head.

In use a match may be withdrawn from the package in the usual manner. When it is desired to ignite the match the package is held by the user as illustrated in Fig. 3, the thumb and fingers of the user's left hand holding the package, as shown, while the match is grasped by the right hand. To ignite the match the head 9 is inserted into the channel near one end and then drawn to the other end of the channel with a quick movement of the right hand. While the match head is thus being drawn through the channel, slight pressure may be exerted by the thumb and fingers of the left hand upon the outer walls of the channel whereby the match head will be subject to contact with a greater area of abrasive material or roughened surface.

In Fig. 4 I have illustrated a second embodiment of my invention wherein the structure is similar to the form shown in Figs. 1, 2 and 3 as consisting of the back 1', the cover 2', the flap 3' and a cartridge of matches 4 secured between the back and the flap by a

staple or other fastener 5'. In the embodiment illustrated in Fig. 4, however, I have formed the match head ignition channel at a point intermediate the cover 2' and the back 1'. In the present form, therefore, the match package consists of a strip or sheet of material formed to provide a flap 3' at one end, the material being bent upwardly upon itself to form the back portion 1'. A channel 15 similar to that shown in Figs. 1, 2 and 3 and described hereinbefore and having abrasive material therein as described hereinbefore, is formed intermediate the back 1' and the cover 2' and has its match head receiving opening exterior to the body of the package.

In use, the package may be grasped in the left hand with the thumb and fingers adjacent the top of the package and on opposite sides of the groove. A match held by the right hand may then have its headed end inserted within the groove near one end. When it is desired to ignite the match, it is drawn quickly through the groove or channel in contact with the abrasive surfaces therein, whereupon the match will be ignited.

In this form of my invention it will likewise be noted that protection from burns and hot sparks is afforded.

I have, as shown in the accompanying drawings illustrating two embodiments of my invention, provided an inexpensive and convenient vest pocket match package containing a cartridge of matches and having a channel or recess formed on the package, whereby the matches may be ignited without danger of flying sparks and consequent burning of clothing and the like, and without the danger of burning the fingers of the user.

By means of my invention I have also provided a device whereby such matches as are usually carried in paper or cardboard packages and are usually of such frail stem construction as to prevent ease of ignition without breaking or bending the stem, may be ignited by use with my package without the danger of breaking or bending.

Various changes may be made in the con-

struction of my device without departing from the spirit of my invention or the scope of the subjoined claims.

What is claimed is:—

1. In a folding match package, a match enclosing wrapper composed in seriatim of a match retaining flap, an end, a back, a hinge end and a hinged cover, a plurality of severable matches having unseverable butt ends secured between the flap and back and rigidly permanently spacing them apart; and an externally concave fold formed in the end between the flap and the back, provided with abrasive match striking material and maintained substantially of preselected shape by the rigidly spaced flap and back. 55

2. In a folding match package, a single piece of material folded to form a match enclosing wrapper composed in seriatim of a match retaining flap, an end, a back, a hinge end and a hinged cover, a plurality of severable matches having unseverable butt ends secured between the flap and back and rigidly 60 permanently spacing them apart; and an externally concave fold formed in the end between the flap and the back, provided with abrasive match striking material and maintained substantially of preselected shape by 65 the rigidly spaced flap and back. 70

3. In a folding match package, a single piece of material folded to form a match enclosing wrapper composed in seriatim of a match retaining flap, an end, a back, a hinge 80 end, and a hinged cover, a plurality of severable matches having unseverable butt ends secured between the flap and back and rigidly permanently spacing them apart; and an externally concave fold formed in the end between the flap and back and shaped in cross section to substantially fit the head of a match and provided with abrasive match striking material and held in said shape by 85 the rigidly spaced flap and back. 90

In testimony whereof I hereunto affix my signature this 2nd day of September, 1925.

H. T. BRADNER.
